Attorney.

UNITED STATES PATENT OFFICE.

HAROLD H. SULLWOLD, OF ST. PAUL, MINNESOTA.

STORM-WINDOW GRAPPLE.

1,223,443.

Specification of Letters Patent.

Patented Apr. 24, 1917.

Application filed September 5, 1916. Serial No. 118,567.

To all whom it may concern:

Be it known that I, HAROLD H. SULLWOLD, a citizen of the United States, residing at St. Paul, in the county of Ramsey and State 5 of Minnesota, have invented a new and useful Improvement in Storm-Window Grap- ples, of which the following is a specifica- tion.

This invention relates to a storm window 10 grapple, the primary object being to pro- vide improved means for assisting in the re- moval and replacement of storm windows and screens.

It has been found in practice very difficult 15 at times and especially in windy weather to handle storm windows and screens when ad- justing them in position in connection with buildings and the primary object of this in- vention is to facilitate such handling, mak- 20 ing it easier to fasten or remove them while the operator is standing within the building and out of the cold.

To this end my invention comprises a pair 25 of tongs peculiarly constructed and oper- ated as will hereinafter be more particularly described and claimed.

In the accompanying drawing forming 30 part of this specification, Figure 1 is a side elevation of my invention and a section of a detail of a sash; Fig. 2 is another view similar to Fig. 1, except that the tongs are in open or disengaging position, and Fig. 3 is an edge view of the tongs.

In the drawing, let A represent a detail 35 of a sash which may be that of a storm win- dow or screen. The head piece of this sash has the usual rabbet 2, molding 3, window glass 4 seated in said rabbet, and putty 5 which serves to assist in holding the glass 40 and seal it in place.

Let B represent my improved grapple, 45 which is composed of a pair of tongs 6 and 7 hinged together between their ends by the pivot 8. The portions of these tongs above said pivot form the power levers 9 and 10 or operating handles, each of which is formed with an eye 11, through which the ropes, cables 12 or other supporting means are passed, one rope being secured through the eye of lever 9 and fastened by the knot 13 or other suitable means and the other rope being se- 50 cured through the eye or lever 10 and se- cured by the knot 14.

That portion of the tongs below the pivot 55 8 is peculiarly formed to embrace the head piece of the sash so that the sash will not

slip or the glass become broken and so that the tongs will open automatically when the sash is lowered and stood on the ground by an operator while the latter remains over- 60 head or within a building. The tongs as shown are made out of two flat pieces of metal or other suitable material which are fastened flatwise together by the pivot 8. The portion 15 of the tong 6 below the 65 pivot is given a quarter turn and bent down- wardly at an angle so that its inner face will lie flat against and embrace the mold side of the head piece of the frame A when the tongs are in closed position. The lower 70 extremity of this member 15 is formed at an inturned angle to produce a jaw 16 which engages over and flat against the surface of the mold 3. The portion 17 of tong 7 is also formed by giving the portion of the tong 75 below the pivot a quarter turn and bending the same downwardly and inwardly so that its inner surface will when the tongs are in closed position lie flat against and embrace the flat surface of the pulley side of the 80 head piece of the frame. The tip of this lower extremity is turned inwardly to pro- duce an inwardly and downwardly inclined 85 jaw member 19 over the putty surface and is blunted by a broad faced shoulder member 20 which may bear against the outer surface of the window glass without breaking or cracking the latter.

In use the operator after loosening the 90 sash from the window frame while standing within a building adjusts the tongs over the head piece of the sash as shown in Fig. 1, and then lowers the sash to the ground be- 95 low, outside the building by the ropes 12. During this operation the tongs are held tightly clasped without slipping or breaking the glass, over the head piece, due to the pressure exerted by supporting the lever arms 9 and 10.

When the sash reaches and stands upon 100 the ground the tongs are spread by lowering them, the inner edges 22 and 23 being shaped at upwardly and inwardly inclined angles which act as spreading surfaces sliding over the upper corners of the sash. This action 105 enables the tongs being easily disengaged and removed from the sash when lifted by one of the ropes. The sash can also be raised into position from the ground when desired. The grapple constructed as de- 110 scribed enables an operator to easily and quickly adjust storm sashes and screens into

and out of position for use while the operator remains indoors and with less work and danger. Its construction is very inexpensive and simple and places within reach a device which fills a long felt want.

In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following claim.

Having described my invention what I claim as new and desire to protect by Letters Patent is:

A window grapple, comprising, in combination, a pair of tongs hinged together by

a pivot, the arms of said tongs above said pivot being formed with eyes, and the arms below said pivot being shaped to correspond with the sides of the cap of the window and formed on their outer extremities with in-turned jaw members, one inclining inwardly closely over the putty surface of the cap and provided with a broad faced stop abutting the window surface, and the other inclining inwardly and conforming with the general trend of the mold surface of the cap, and a pair of cords secured to said tongs through said eyes, said arms immediately below said pivot being formed with downwardly and outwardly inclined inner edges serving to spread the tongs apart when the cords are released.

In testimony whereof, I have signed my name to this specification.

HAROLD H. SULLWOLD.
